HOLDER FOR ROLLS OR SHEETS OF PAPER

John Lawrence Candler, London, England

Application May 6, 1939, Serial No. 272,077
In Great Britain May 9, 1938

14 Claims. (Cl. 91—38)

This invention relates to holders for rolls or sheets of paper or to devices associated therewith.

In the furtherance of personal cleanliness it may be desirable to employ paper in a moistened or damp condition and it is the primary object of this invention to provide an improved device for this purpose.

While the primary object of the invention is to provide a device which facilitates personal cleanliness after a bowel action the use of the device is obviously not limited to such application. A similar device to what is normally termed "a toilet fixture" may be used, for example for distributing moistened and dry paper towels for cleaning or freshening the face, hands or the like.

A further object of the invention is to provide a paper-distributing device which is particularly applicable in cases of certain bodily disorders, notably "haemorrhoids." The manner in which the above general objects of the invention are attained may best be understood from a consideration of the subsequent part of this specification in which by way of example, but without limitation suitable examples of paper-distributing devices embodying the invention are described.

In the accompanying drawings illustrating several examples and forming a part of this specification:

Fig. 1 is a front elevation of a device embodying the invention for distributing moistened or dry paper from a roll;

Fig. 2 is a side elevation partly in section of the corresponding device;

Fig. 3 is a view corresponding to Fig. 2 of the operative mechanism for applying moisture to the paper;

Figs. 4 and 5 show diagrammatically in side view partly in section a modified embodiment of the device for applying moisture to paper stacked in sheets.

Referring to Figs. 1-3 there is provided an outer casing denoted generally by 10 which is preferably of substantially rectangular shape and is formed at its upper end with a cover member 11 pivotally mounted about axis 12 and which is maintained in its covering position by suitable spring catches 13.

On the lateral walls of the casing 10 are mounted supporting lugs 14 each having an inclined slot 15. The slots are adapted to receive the spindle 16 of a paper roll holder 17 indicated diagrammatically in Fig. 1. Any suitable form

of roll holder may be provided and in the embodiment illustrated the spindle 16 comprises two telescopic portions adapted to be mutually separable to allow the insertion of the holder into the paper roll and carrying two sleeves 18, 19 having conical heads 20, 21 slidably mounted on the spindle 16 and controlled as to their position by compression springs 22. The paper roll indicated generally by 23 thus centers itself on the conical heads 20, 21 which adjust themselves according to the axial width and bore diameter of the paper roll.

The upper ends of the slots 15 are closed by the cover member 11. Mounted on the inside of the cover 11 is a retaining leaf-spring 24 which retains the roll and roll holder in position in the slots 15 and prevents the roll from overrunning. Adjacent the lower edge of the cover 11 is formed in the front wall of the casing 10 a slot 25 through which the paper from the roll 23 is adapted to project and through which the said paper is withdrawn. At its lower end the cover 11 carries in rotatable manner a roller 26 mounted rigidly on a spindle 27, the roller and spindle rotating as a unit.

At the lower end of the casing 10 is arranged a tank 28 adapted to hold liquid and removably mounted within the casing 10, for example held frictionally by a plurality of leaf-springs 29 mounted on the inside of the casing 10. Slidably mounted on a cross-bar 30 fixed to the lateral walls of the casing 10 are guide members 31 which are axially separable according to the width of the paper roll so as to guide the paper within the slot 25. The guide members 31 project slightly through the slot 25 and at their front ends are provided with laterally turned-up members 32 which assist in guiding the paper.

Disposed at the lower end of the casing is a device for transferring liquid from the tank 28 to the lower side of the paper prior to issuance of the latter from the slot 25. The liquid-applying member preferably comprises a sponge-rubber pad 33 which is mounted at each end on an arm 34 pivotally movable about an axis pin 35. Mounted below the pad 33 is an anti-splash or damping plate 36 which remains immersed in the liquid in the tank and prevents up and down movement of the pad 33 from creating excessive splashing of the liquid in the tank 28.

The mechanism for actuating and controlling the time of application of the pad 33 to the paper from the roll 23 in the illustrated embodiment is as follows. Pivotally mounted about pivots 37 at each side of the casing are levers 55

38 which at their front ends project through slots 39 in the front wall of the casing and carry finger actuating studs 40. The levers 38 are connected by a pin and slot connection 41, 42 with a link 43 which connection allows lost motion between the link 43 and the lever 38. At its upper end each link 43 is connected to a lever 44 pivotally mounted on the axis 35. At the front end of one lever 44 is mounted an arcuate cam 45 which is arranged for pivotal movement about a pin 46. A torsion spring 47 is disposed around the pin 46 and engages at one end against the lever 44 and at the other end against the arcuate cam 45 in such manner as to tend to force the cam 45 upwardly in a clockwise direction. In its normal inoperative position the leading edge of the arcuate cam bears against the underface of the spindle 27. Pivotally mounted on the lateral wall of the casing 10 for movement about the pivot 48 is a cam stop 49 having a finger control member 50.

The movement of the pad 33 is determined by a tension spring or like resilient member 51 which is connected between the lever 44 and the lever 38. A further spring 52 is interposed between the lever 38 and the lever 44 acting as a return spring to return the lever 38 with the finger stud 40 to its upper position on release of finger pressure.

Preferably a guide plate 53 is mounted on the outside of the front wall of the casing adjacent the slot 25 to facilitate the tearing off of the paper passing through the slot. If desired, the members projecting from the front wall of the casing may be shrouded by a shroud member 54 which is pivotally mounted about studs 55 and held in its shrouding position by a spring or springs 56. The mounting of the spring 56 is preferably such that when the cover is swung 40 into the downward position shown in Fig. 3 to allow access to the actuating mechanism the spring 56 acts as a toggle-spring and maintains the cover in its lower position.

In operation the paper strip 60 from the roll 23 is led downwardly below the guide roller 26 and passes through the slot 25 in which it is controlled as to its lateral position by the resilient guide members 31 and 32. In the normal position of the actuating mechanism shown in Fig. 2 the paper withdrawn will be in a dry condition. If it is desired to apply moisture to the paper one or other of the finger studs 40 is depressed which moves the corresponding lever 38 about its pivot 37 thereby lowering the rear end of the lever 44 through the intermediary of the link 43. The raising of the front end of the lever 44 lifts the pivot 46 so that the arcuate cam 45 which is stressed by the spring 47 so as to move upwardly is lifted to such a position as to release its leading edge from the spindle 27 so that the arcuate cam rotates about its pivot 46 until the tail 51 of the cam comes in contact with the stop pin 49 as shown in Fig. 3. In this position the arcuate face of the cam 45 bears frictionally against the spindle 27 when pressure on studs 40 is released.

At the same time due to the raising of the lever 44 the sponge-rubber pad 33 is lifted through the intermediary of the spring 51 so that it bears resiliently against the lower face of the paper strip 60 at the point where the latter engages around the guide roller 26. On withdrawing the paper strip 60 the underface of said strip is moistened by the sponge-rubber pad.

75 The extent to which the strip 60 is moistened

is determined by the arcuate cam 45 which on rotation of the roller 26 and spindle 27 gradually moves downwards in a counter-clockwise direction due to its frictional engagement with the spindle 27. When the leading edge of the arcuate cam 45 moves off the spindle 27 the entire actuating mechanism including the pad 33 and the actuating levers fall downwardly due to gravity so that the arcuate cam again takes up the position shown in Fig. 2 with its leading edge bearing against the spindle 27.

The time period during which the pad 33 remains in contact with the underface of the paper strip 60 and thus the wetted length of paper is dependent on the length of contact of the arcuate cam 45 with the spindle 27 and this in turn is dependent on the original position of the cam 45 after depression of the actuating mechanism 40, 38. The position of the cam 45 can be adjusted by adjustment of the stop 49. In other words, raising of the stop 49 through the actuating finger 50 will shorten the arcuate length through which the cam 45 frictionally engages the spindle 27 and thus shortens the length of the underface of the paper strip 60 wetted by the pad 33.

It is to be noted that when finger pressure is released from the finger stud 40 after setting the actuating mechanism the lever 38 and stud 40 move back into the dotted position shown in Fig. 3 under the action of the spring 52. It will also be noted that the pad 33 is retained in its operative position until a controlled length of the paper strip has been withdrawn and that the same then automatically moves downwardly into its inoperative position.

The liquid content in the tank 28 may, for example comprise water, a dilute disinfectant, diluted perfume or any other suitable liquid.

In Figs. 4 and 5 is diagrammatically illustrated the mechanism for a holder intended to contain a stack of sheets of paper as is commonly sold for use with toilet fixtures. The sheets of such paper stacks are usually folded or otherwise inter-leaved to ensure that on the withdrawal of the outside sheet the succeeding sheet is brought into position for withdrawal.

The apparatus shown in Figs. 4 and 5 comprises a casing 10 provided with an enlarged slot opening 71 on its front face through which the paper sheet is adapted to project. Such a sheet is illustrated diagrammatically in Fig. 4 at 72. Mounted for vertical sliding movement in the lateral wall of the casing is a frame structure comprising two vertical uprights 73 carrying at their upper ends a roller 74 fixed on a rotatable spindle 75. The frame is steadied at its lower end by levers 76 fixed to a common spindle 34, the levers having a slot 77 engaging around a pin 78 mounted on the frame. The frame is provided with a manually actuated member 79 formed with a finger stud 80.

The pad 81 is mounted on a spindle 82 carried in suitable supports, for example on the lateral walls of the casing and the said spindle also carries a pulley 83. Engaging around the pulley 83 is a steel tape or like transmission member 84 which is secured at one end to the pulley as by a screw 85, and is connected at its other end to the pin 78. Intermediate the ends of the steel tape 84 is a tension spring or like member 85.

A sector-shaped cam 86 is mounted for pivotal movement about an axis pin 87 and is provided with an arcuate face 88. A torsion spring 89 tends to urge the cam 86 in a counter-clockwise

direction and the upper position of the cam is determined by a stop 90 which is adjustable as regards its vertical position, for example is vertically movable within a suitable guide 91.

5 Located at the lower part of the casing 70 is a tank or other container 92 which may, for example be removed to the front of the casing. In addition, the casing 70 is provided with a removable cover 93 to allow replacement of the paper 10 stack.

Fig. 4 shows the arrangement of parts in inoperative position in which sheets of paper 72 may be withdrawn in a dry condition.

If it is desired to moisten a sheet the finger 15 stop 80 is depressed thereby moving the frame structure into the position shown in Fig. 5. Downward movement of the pin 78 causes rotation of the pulley 83 through the intermediary of the transmission tape 84 and spring 85 and 20 causes movement of the pad 81 into the position where it contacts against the paper on the underside of the roller 74.

As in the last-described embodiment downward movement of the frame structure moves the cam 25 86 against the force of the spring 89 until the cam is able to take up the position shown in Fig. 5 where its arcuate surface 88 bears against the spindle 75 and its upper edge abuts against the stop 90.

30 Rotation of the roller 74 on withdrawal of the paper strip 72 causes rotation of the spindle 75 and clockwise movement of the cam 86 until its arcuate surface 88 passes below the spindle 75 in which case the entire framework moves upwardly under the action of the springs 89 and 85. Simultaneously the moistening pad 81 returns 35 into the position shown in Fig. 4.

The extent of the moistened surface of the paper 72 is dependent on the time of engagement 40 of the cam surface 88 with the spindle 75 and this length can be adjusted by adjustment of the stop 90.

It will be understood that the invention contemplates within its scope devices which may 45 vary from the specific examples hereinbefore described by way of illustration and the invention is accordingly to be understood as embracing all structures falling within the scope of the appended claims.

50 What I claim is:

1. A holder for rolls or sheets of paper which includes a normally inoperative device for applying liquid to a surface of said paper during withdrawal of the latter from the holder, an actuating member for bringing said device into a liquid-applying position and means responsive to movement of the paper for restoring said device into its inoperative position.

2. A holder for rolls or sheets of paper which 60 includes a normally inoperative device for applying liquid to a surface of the paper during withdrawal of the latter from the holder, an actuating member for bringing said device into a liquid applying position and means responsive to movement of the paper for restoring said device into 65 its inoperative position, said means being adjustable to vary the length of paper wetted.

3. A holder for rolls or sheets of paper which 70 includes a casing having a withdrawal slot, a normally inoperative device for applying liquid to a surface of said paper during withdrawal of said paper through said slot, a roller rotatably mounted on said casing and located adjacent said 75 slot, the paper being led below and in contact

with said roller, manually actuated means for lifting said liquid-applying device against the paper contacting said roller, means to hold said liquid-applying device in its raised position and means controlled by the movement of said 5 roller to so release said liquid-applying device that it falls under the force of gravity into its inoperative position.

4. A holder for rolls or sheets of paper which includes a casing having a withdrawal slot, a normally inoperative device for applying liquid to a surface of said paper during withdrawal of said paper through said slot, a spindle rotatably mounted on said casing, a roller carried by said spindle and located adjacent said slot, the paper 10 being led below and in contact with said roller, manually actuated means for lifting said liquid-applying device against the paper contacting said roller, means engaging said spindle to hold said liquid-applying device in its raised paper-contacting position, and means operative by a predetermined rotational movement of said spindle 20 to move said holding means out of its operative position whereby said liquid-applying device returns to its inoperative position under the force 25 of gravity.

5. A holder for rolls or sheets of paper which includes a casing having a withdrawal slot, a normally inoperative device for applying liquid to a surface of said paper during withdrawal of 30 said paper through said slot, a spindle rotatably mounted on said casing, a roller carried by said spindle and located adjacent said slot, the paper being led below and in contact with said roller, manually actuated means for lifting said liquid-applying device against the paper contacting said roller, holding means for said liquid applying device comprising a spring controlled cam having an arcuate surface, and means to bring said surface into frictional engagement with said spindle on operation of said manual actuating means to hold said liquid applying device in its raised position, said cam after a predetermined rotation of said spindle being rotated clear of said spindle to thereby release said liquid applying device. 40

6. A holder for rolls or sheets of paper as claimed in claim 5, which includes means to adjust the initial setting of the cam surface relatively to the spindle on raising the liquid applying device whereby the length of paper moistened 50 may be varied.

7. A holder for rolls or sheets of paper which includes a normally inoperative device for applying liquid to a surface of the paper during withdrawal of the latter from the holder, an actuating member for bringing said device into a liquid-applying position, resilient means interposed between said actuating member and said liquid-applying device to provide a predetermined pressure of said liquid-applying device in its 60 operative position and means responsive to movement of the paper for restoring said device into its inoperative position.

8. A holder for rolls or sheets of paper as claimed in claim 1, in which a liquid container is 65 located at the lower end of the casing to contain liquid for moistening the liquid-applying device in its inoperative position.

9. In a holder for rolls or sheets of paper as claimed in claim 1, the provision of a damping 70 plate on the liquid-applying device which remains constantly immersed in liquid throughout the movement of said liquid-applying device.

10. A holder for rolls or sheets of paper as claimed in claim 3, which includes resilient guide 75

- elements laterally positioning the paper and maintaining the paper in contact with the roller.
11. A holder for rolls or sheets of paper as claimed in claim 1, which includes a lost-motion device interposed between the actuating member and liquid-applying device whereby said actuating member may be restored to its normal position prior to the resortation of said liquid-applying device into its inoperative position.
12. A holder for rolls of paper as claimed in claim 3, which includes a pivotal cover on the casing, inclined guideways on the lateral walls of said casing and a support for the paper roll disposed within said guideways, the guideways being disposed so as to be closed by said cover.
13. A holder for rolls of paper as claimed in claim 3, which includes a guide plate disposed on the outside of the casing adjacent the withdrawal slot.
14. A holder for rolls of paper as claimed in claim 3, which includes a pivotal cover on the casing, inclined guideways on the lateral walls of said casing disposed so as to be closed by said cover, a support for the paper roll located within said guideways and means on said support for automatically centering the roll of paper independently of its length and bore diameter.

JOHN LAWRENCE CANDLER. 15
